OF LAPORTE, INDIANA, A CORPORATION OF ILLINOIS.

PIANO-ACTION.

1,079,435.

Specification of Letters Patent. Patented Nov. 25, 1913.

Application filed March 19, 1913. Serial No. 755,271.

To all whom it may concern:

Be it known that I, FRANK PECK, a citizen of the United States, residing at La-
porte, in the county of Laporte and State
5 of Indiana, have invented certain new and
useful Improvements in Piano-Actions, of
which the following is a specification.

This invention pertains in general to
piano actions and has more particular ref-
10 erence to the mechanism for operating the
hammer.

One of the primary objects of the present
invention is to provide a piano action in
15 which the hammer will be positively re-
turned, after its operating stroke, by the
operating jack upon its return movement,
thereby eliminating from the action the
usual bridle wire, bridle tape, bridle strap
20 and the guiding portion of the back stop
through which the bridle tape is customarily
threaded. My invention, therefore, simplifies
the construction of the action, reduces
its cost of manufacture and decreases the
liability of the action to get out of order.

25 Other objects and advantages of the in-
vention will be readily apparent to those
skilled in the art as the same is better un-
derstood by reference to the following de-
scription when considered in connection
30 with the accompanying drawings.

Referring to the drawings—Figure 1 is a
side elevation of a piano action embodying
my invention; Fig. 2 is a longitudinal sec-
35 tional view taken through the hammer butt;
showing the pin before it has been bent to
operative position. Fig. 3 is a sectional view
taken substantially on the line 3—3 of Fig.
2; and Fig. 4 is a perspective view of a
40 hammer butt pin before it has been applied
to the hammer butt.

On the drawings reference character 5 in-
dicates the rail or support extending length-
wise of the piano upon which various parts
of the mechanism are mounted. A block
45 6, commonly known as a damper flange, is
mounted upon the upper edge of the rail
5 and has a pair of ears projecting back-
wardly from the rail between which the
damper lever 7 is pivotally mounted on the
50 pintle 8. A damper block 9 is mounted
upon the upper end of the damper lever
and carries a damper 10 which is normally
urged into engagement with the piano wire

11 by a spring 12 mounted upon the damper
flange 6. 55

A butt flange 13 somewhat similar in con-
struction to the damper flange 6 is secured
to the front face of the rail 5 and the ham-
mer butt 14 is pivotally mounted between
the ears of the flange upon a pin or pintle 60
15. A hammer shank 16 fixed to the ham-
mer butt carries at its upper extremity a
hammer 17 of well known or preferred con-
struction which is adapted to strike the wire
11 in the usual manner upon actuation of 65
the hammer butt, the customary hammer
rest rail 18 being positioned rearwardly of
the hammer shank to form a rest for the
hammer when in inoperative position. The
hammer is normally urged into the inop- 70
erative position shown by a light butt spring
19 carried by the spring reel 21.

The wippen 22 is pivotally mounted at 23
between the ears of a block or flange 24
fixed to the rear face of the rail 5, said 75
wippen carrying at its rear end an upwardly
projecting spoon 25 adapted to operate the
damper lever 7 upon actuation of the wip-
pen. A member 26 pivotally connected at
27 to the wippen projects downwardly in 80
position to be operated by the rear end of
the key lever 28 in the usual manner. A
back-check 29 is carried by a back check
wire 31 rigidly mounted in the wippen, this
back-check being adapted to be engaged by 85
the back-stop 32 carried by a shank 33 fixed
to the hammer butt 14. The hammer is ac-
tuated by an operating device or jack 34
pivotally mounted at 35 between the ears of
a block 36 which is fixed to the wippen 22. 90
The jack has, at its lower end, a forwardly
extending arm or finger 37 and an expansion
spring 38 is interposed between this finger
and the wippen 22 to normally urge the
jack in a clockwise direction about its pivot. 95
A regulating screw 39 mounted in a suitable
block 41 carries a buffer 42 which is disposed
in the path of the finger 37 so that, upon
upward movement of the wippen and jack,
the jack is swung in a counter-clockwise 100
direction on its pivot and against the force
of the spring 38 by engagement of the arm
37 with the buffer.

The parts thus far described, with the ex-
ception of the novel formation of the upper 105
end of the jack which will be more fully

brought out hereinafter, are of usual and well known construction and operate in a manner which is familiar to those skilled in the art. In order to insure a positive return of the hammer, it has been customary 5 heretofore to attach one end of a bridle tape to the hammer butt at the base of the back stop shank 33, the other end being equipped with a leather bridle strap which is connected with a bridle wire extending 10 from the wippen parallel with and behind the back-check shank 31. The lower end of the back stop was also elongated and provided with an aperture through which 15 the bridle tape was threaded, the back stop thereby serving as a guide for the bridle tape between its ends. These bridle tapes have always been a source of trouble and annoyance in pianos for the reason that in 20 assembling a piano the adjustment of the bridle wires consumed considerable time and required no little skill and, also, for the reason that if a mouse or rat gets into the piano it will invariably gnaw the tapes, thus impairing, if not entirely destroying, 25 the proper operation of the action.

My present invention is designed to eliminate the bridle tapes and their accessories from the action and, with this end in view, 30 I have provided a construction, which will now be described, whereby the hammer is positively returned directly by the jack upon its return movement. The lower face of the hammer butt 14 is curved and covered with 35 a wearing buffer 43 of leather, or other suitable material, in the usual manner, strips 44 of softer material being preferably interposed beneath the lower portion of the wearing buffer to absorb the shocks incident to 40 the initial upward movement of the jack 34 and to ease the action. Adjacent the ends of the strip 43 and the lower strip 44 the hammer butt is provided with an inclined socket adapted to receive a pin 45 which is 45 threaded into the socket the required depth and then bent downwardly as shown in dotted lines in Fig. 2 to seat in a groove 46 formed on the front face of the hammer butt beneath the socket. The extremity of 50 the pin is bent as indicated at 47 to project toward the jack 34 and the bend in the pin and the groove in which the bent portion of the pin lies prevent turning of the pin in the socket, thereby insuring that the projecting end 47 will always be disposed in 55 proper relation to the jack. After the pin has been positioned in the hammer butt a pad of felt 48, or other similar material, may be secured over the groove and pin 60 therein to provide a cushion against which the end of the jack 44 may strike, thereby obviating shocks and noise. The jack 34 is provided adjacent its upper extremity with a recess forming a shoulder 49 which 65 is preferably faced with buckskin or other

similar material, and is adapted to engage with the end 47 of the pin 45 upon the return stroke of the jack, thereby pulling downwardly upon said pin and positively returning the hammer to inoperative position against the rail 18. The bent pin and the coöperating shoulder on the jack are adapted, therefore, to perform the same function that the bridle tape and mechanism associated therewith, has heretofore performed, the present construction being much simpler, more positive in its action and much less liable to get out of order. 70 75

When the wippen is swung in a clockwise direction about its pivot 23 upon the operation of a piano key, the jack is moved upwardly to swing the hammer butt on its pivot and cause the hammer to strike its wire or string. When the finger 37 of the jack contacts with the buffer 42 the jack is 80 swung on its pivot away from the hammer butt thereby permitting the hammer to be thrown back by the butt spring 19 until the back stop 32 strikes the back-check 29. Reverse movement of the wippen will withdraw the back-check and retract the jack. 85 As the jack travels downwardly the spring 38 will cause the shoulder 49 to overlie the end 47 of the pin so that the hammer butt will be positively swung in a counter-clockwise direction on its pivot to return the hammer to inoperative position against the hammer rail. 90 95

It is believed that my invention and its mode of operation will be fully understood from the foregoing without further description and, while I have shown and described a preferred embodiment of the invention, it will be manifest that the structural details disclosed may be varied within considerable limits without departing from the scope of the invention as set forth in the following claims, or sacrificing any of the material advantages thereof. 100 105

I claim:

1. A piano action comprising a jack, a hammer butt provided with a socket and a groove at the mouth of the socket disposed at an angle to the socket, and a pin threaded into said socket and bent at the mouth of the socket to lie in said groove whereby turning of the pin is prevented, the free end of the pin being bent outwardly toward the jack in position to be engaged thereby upon return movement of the jack. 110 115

2. A piano action comprising a hammer butt provided with a socket and a groove at the mouth of said socket disposed at an angle to the axis of the socket, and a pin having one end threaded and its other end bent at an angle to the threaded portion, said pin being threaded into said socket and bent at the mouth of the socket to lie in said groove with the bent end projecting from said groove. 120 125 130

3. A piano action, comprising a jack, a hammer butt positioned to be operated by said jack and provided with a socket and a groove at the mouth of the socket disposed at an angle thereto, and a pin positioned in said socket and bent to lie in said groove whereby turning of the pin is prevented, | the free end of the pin being bent toward the jack to be engaged thereby upon return movement of the jack.

FRANK PECK.
